US00D484311S

(12) **United States Design Patent** (10) **Patent No.:** **US D484,311 S**
Cacka et al. (45) **Date of Patent:** **** Dec. 30, 2003**

(54) **DISPOSABLE TOOTHBRUSH**

(75) Inventors: **Joe W. Cacka**, Berthoud, CO (US); **Howell H. Chiles**, Fort Collins, CO (US); **Clifford J. Snyder**, Fort Collins, CO (US); **Robert L. Callaghan**, Fort Collins, CO (US)

(73) Assignee: **Water Pik, Inc.**, Fort Collins, CO (US)

(**) Term: **14 Years**

(21) Appl. No.: **29/135,573**

(22) Filed: **Jan. 12, 2001**

(51) LOC (7) Cl. **04-02**

(52) U.S. Cl. **D4/101**

(58) Field of Search D4/104-112, 132-134, D4/138; 15/143.1, 159.1, 160, 167.1, 167.2; 132/308; 601/139, 141

(57) **CLAIM**

The ornamental design for a disposable toothbrush, as shown and described.

DESCRIPTION

FIG. 1 is a right side perspective view of a disposable toothbrush showing our new design;

FIG. 2 is a front elevation view thereof;

FIG. 3 is a rear elevation view thereof;

FIG. 4 is left side elevation view thereof;

FIG. 5 is right side elevation view thereof;

FIG. 6 is top plan view thereof; and,

FIG. 7 is a bottom plan view thereof.

1 Claim, 3 Drawing Sheets
